EYE-SHADE

Elias Edward Resk, 442 E. 20th St., New York, N.Y.

Filed Mar. 8, 1963, Ser. No. 73,895

Term of patent 14 years

(Cl. D57—1)

FIGURES 2-4 are plan, side, and front views thereof, respectively.

The broken lines shown in the drawing are for illustrative purposes only.

I claim:

The ornamental design for an eye-shade, substantially as shown and described.
